UNITED STATES PATENT OFFICE.

WILLIAM S. BARTHOLOMEW AND PLATO G. EMERY, OF CHICAGO, ILLINOIS,
ASSIGNORS TO THE ADAMS & WESTLAKE COMPANY, OF ILLINOIS.

WINDOW-CURTAIN.

SPECIFICATION forming part of Letters Patent No. 624,735, dated May 9, 1899.

Application filed February 17, 1899. Serial No. 705,838. (No model.)

To all whom it may concern:

Be it known that we, WILLIAM S. BARTHOLOMEW and PLATO G. EMERY, of Chicago, in the county of Cook and State of Illinois, have invented certain new and useful Improvements in Window-Curtains, of which the following is a specification, reference being had to the accompanying drawings and to the numerals of reference marked thereon.

10 Our invention relates to such curtains or shades as are designed for use in railway-cars, more especially of the type known as "open" or "summer" cars.

15 As is well known, inconvenience is experienced by passengers when the curtains or shades of an open or summer car are drawn down or closed by reason of the exclusion of light and the inability of the passengers to look out to determine their locality, so as to indicate to the conductor when to stop the car. To obviate such inconvenience, we in carrying out our invention insert in the frame or between the uprights or posts of such a car, near the top, a glazed window-sash adapted to have 25 free vertical movement and remove that section of the curtain or shade which would be opposite said window-sash when the curtain or shade is drawn down to its lowest limit. The construction and arrangement are such 30 that when the curtain is run up the window sash or frame is suitably engaged, as by the curtain-stick, and lifted until concealed within the casing of the car.

35 In the further description of our invention which follows reference is made to the accompanying drawings, in which—

Figure 1 is a view of our invention as seen from the outside of the car, the curtain being drawn down to its lowest limit and the window-sash in position to admit light to the interior of the car. Fig. 2 is a similar view from the interior of the car, a portion of the framing being removed to better illustrate the parts. Fig. 2^a is a similar view showing a modified 45 form of shade. Figs. 3, 4, and 5 are sections on the line 3 5 of Fig. 1, showing the shade illustrated in Fig. 2^a and the window-sash in different positions. Fig. 6 is a horizontal section on the line 6 6 of Fig. 1.

50 Similar numerals of reference indicate similar parts in the several figures.

11 represent the side posts, uprights, or frames of a car, preferably of the summer or open type or other structure, to which our invention may be applicable.

55 2 is a curtain or shade of any suitable material or construction, the one here shown being of the well-known "Acme" type, which is used with a spring or "Hartshorn" roller 4 and in which the curtain-stick 3 is retained in 60 parallelism with the roller by means of guiding-cords 5. It is obvious, however, that the invention is adapted to a curtain or shade of different description.

65 In the form of invention preferred and here shown each end of the curtain-stick 3 is provided with a lug 6, extending outwardly, as illustrated in Figs. 1, 3, 4, and 5, the function of which lugs will be hereinafter described.

70 Between the uprights or posts 1 and near the top of the car is arranged, so as to move freely in vertical guides, a glazed window-sash 7, its extreme length being preferably equal to the width of the opening between the uprights and the width of the glazed portion 75 about six inches, more or less. Attached to each post or upright 1, near its upper end, is a plate 8, having a rib 9 projecting inwardly therefrom, as shown more particularly in Fig. 6, and each end of the window-sash 7 is 80 grooved, as at 10, one of the ribs 9 entering each groove, there being thus formed a guide or way in which the window-sash slides. Stops 11, attached to the side posts or uprights below the window-sash, limit its downward 85 movement. The stops are preferably cushioned with rubber, as at 12, they being made to incase the rubber cushions.

90 A section of the upper part of the curtain or shade 2 may be cut out or removed, or the arrangement may be as seen in Fig. 2, in which the top of the curtain (when the curtain is in its lowest position) is a short distance below the glass of the window-sash, the curtain being connected to the spring-roller 95 4 by means of straps 13. When the curtain or shade is in its lowest position, as seen in Figs. 1, 2, and 3, the window-sash 7 rests on the stops 11 below the side board 14 at the top of the car, permitting the entrance of light 100 through the glazed portion and the opening in the curtain opposite the glass. On running

up the curtain the lugs 6 of the curtain-stick 3 engage the lower edge of the window-sash 7, (see Fig. 4,) and as the curtain is run up the window-sash is lifted until it is hidden behind the side board 14. (See Fig. 3.) When the curtain is pulled down, the window-sash 7 falls by gravity until its rests on the lugs 11.

It is to be observed that the window-sash 7 can never obstruct the entrance of passengers to the car, inasmuch as when the curtain is raised to allow ingress to the car the window-sash is raised with it.

While we have described our invention as more especially adapted for use with an open or summer car, it is also applicable to a closed car, and the drawings illustrate such latter use.

In the use of the word "curtain" throughout this specification we wish it understood that it is intended to include a slatted blind or other appendage of a window, door, or similar opening.

It is obvious that the invention admits of change in details of construction and combinations not involving invention.

Having thus described our invention, we claim—

1. In a car, the combination of a vertically-adjustable curtain or shade, a movable window-sash, and means for operating the sash by the upward movement of the said curtain or shade, substantially as set forth.

2. In combination with suitable framing, a movable window-sash, a vertically-adjustable curtain or shade, a curtain-stick, and means on the curtain-stick for engaging and lifting the window-sash, substantially as set forth.

3. In combination with suitable framing, a window-sash movably mounted therein, a curtain or shade adapted to be raised or lowered, and means on the curtain or shade for raising the window-sash, substantially as set forth.

4. In combination with suitable framing, a window-sash movably mounted therein, a curtain or shade adapted to be raised or lowered,

and lugs at the lower end of the curtain for engaging with the window-sash when the curtain is raised, substantially as set forth.

5. In combination with suitable framing, a window-sash movably mounted therein, a curtain or shade adapted to be raised or lowered and having an opening therein, which opening is opposite the window-sash when the curtain or shade is lowered, and means on the bottom of said curtain or shade for lifting the window-sash when the curtain is raised, substantially as set forth.

6. In combination with suitable framing, a window-sash arranged to slide therein, a curtain or shade adapted to be raised or lowered, lugs on the curtain or shade for lifting the window-sash as said curtain or shade is raised, and stops on the framing for limiting the downward movement of the window-sash when the curtain is lowered, substantially as set forth.

7. In a car, the combination with the framing, of a curtain or shade adapted to move vertically therein, said curtain or shade having an opening in its upper end, a window-sash slidably mounted in the framing opposite the opening in said curtain or shade, and means near the bottom of the curtain or shade for lifting said window-sash when the curtain or shade is raised, substantially as set forth.

8. In combination with suitable framing, a movable window-sash, a vertically-adjustable curtain or shade having an opening in its upper end, a curtain-stick, lugs on the curtain-stick for raising the sash, and stops on the framing for supporting the window-sash when lowered, substantially as set forth.

In testimony whereof we hereunto set our hands and seals.

WILLIAM S. BARTHOLOMEW. [L. S.]
PLATO G. EMERY. [L. S.]
